UNITED STATES PATENT OFFICE.

CHARLES E. WAREAM, OF CINCINNATI, OHIO, ASSIGNOR TO THE AMERICAN LAUNDRY MACHINERY COMPANY, OF NORWOOD, OHIO, A CORPORATION OF OHIO.

DELINTING DRYING TUMBLER.

Application filed April 23, 1920. Serial No. 376,036.

To all whom it may concern:

Be it known that I, CHARLES E. WAREAM, a citizen of the United States, residing at Cincinnati, in the county of Hamilton and State of Ohio, have invented certain new and useful Improvements in Delinting Drying Tumblers, of which the following is a specification.

This invention relates to the art of laundry apparatus and more especially to drying machines, as for instance the tumbler type, the purpose of this invention being to remove the lint from the air after its passage through the drying chamber. In this way such lint is prevented from passing through the fan which is used for forcing the air through the machine, and such lint will also not be allowed to pass to the outside atmosphere or to be further circulated through the machine.

The tumbler type of drying apparatus includes, in a general way, an air chamber, a heating chamber, and a drying chamber, all of these chambers having communication so that air from the outside atmosphere can be forced by means of a fan located in the air chamber through the heating chamber in which is enclosed some means for heating the air, thence through the cylinder of foraminous material in which the laundry is placed for drying and which receives a backward and forward rotating motion, from which point the air is forced back into the air chamber. In such device this air might be recirculated over the same course just re-cited or blown by means of the fan through an outlet to the atmosphere surrounding the machine casing. In either case it is desirable to remove the lint from the air after its passage through the drying chamber.

This invention might be embodied in different forms of structure but the preferred form will be fully understood from the following description and claims considered in connection with the accompanying drawings.

Fig. 1 is an elevation of the tumbler type of dryer with a part broken away; Fig. 2 is a transverse sectional view taken on line $a-a$, Fig. 4; Fig. 3 shows an elevation of the pawl and ratchet mechanism for operating the delinting device; Fig. 4 is a front elevation with parts broken away;

Fig. 5 shows in perspective detail the lint conveyor; while Fig. 6 shows in perspective the lint screen.

By means of a fan indicated at 1 in Fig. 2, fresh air from the outside atmosphere is forced through the warming chamber, not shown in the present drawings, thence through the drying chamber 2 within which is enclosed the tumbler with its foraminous wall 3, from which point the air is forced into air space 6 and back to the fan again to be forced through the same circuit or to be partly forced to the outside atmosphere, as the case may be. A door 4 hinged to the foraminous cylinder 3 allows access to the interior thereof. Upon opening door 5 which is hinged upon the outside casing for the removal of the laundry, the delinting device is operated through a certain mechanism which will now be described, the delinting device proper being located in the lower part of the air space 6 between the drying chamber and the fan casing as shown in Fig. 2.

Through the mechanism comprising a motor 31 which drives pinion 30 and in turn the meshing gear 28 which carries pinion 29, gear 27 meshing with pinion 29 and the main gear 26 on one of the trunnions of the tumbler, backward and forward motion is transmitted to the drying cylinder 3 and likewise to the ratchet 23 mounted upon the shaft of gear 26, this ratchet 23 having cooperation with pawl 24 mounted upon the gear 22 which is loosely mounted upon the trunnion of gear 26. Then by means of a chain or belt connection 32 between sprockets 22 and 33, operation of the delinting conveyor 16 upon shaft 34 is effected; that is, when shaft 25 with its ratchet 23 is operating in clockwise direction, pawl 24 during the reverse direction riding freely upon ratchet 23. The mechanism for giving the intermittent backward and forward motion to the tumbler 3 is not shown herein as this means is well known in the art.

Upon opening or closing door 5, which carries near its lower edge, as shown at 21^a, a finger 21 with a curved or cam shaped portion near its inward end, rod 17 is given a downward motion by engagement of the cam 21 upon roller 19 against action of the spring 20 mounted on said rod between the guide 18 and the clevis 19' in which is

mounted roller 19 at the upper end of the rod 17. The lower end of rod 17 has pivotal connection at 16' with lever 15'. This downward motion is communicated through 5 connection 15' to horizontal axis 15 upon which is mounted a pair of lever arms 40. Lever arms 40 carry at their inward ends rollers 14 which bear against strips 35 on the inclined screen member 10 hinged at its 10 lower edge as shown at 13 in Fig. 2. As shown in Fig. 1, finger 21, rod 17 and lever 15' are outside the casing, while lever arms 40 are inside. Thus the screen member 10 as a result of such operation is caused to 15 move backwardly toward the stop 11 mounted upon the lower part of the partition surrounding the drying chamber. Then, when cam member 21 has passed entirely over idler 19, this screen member 10 is allowed to fall by gravity against the stop 12 which is provided on the extension 9 of the partition member surrounding the drying chamber. The extension of this 20 partition member cooperates with the like member 8 to form a passage-way for the air from the drying chamber to the delinting device. The wall member 8 just referred to is a continuation of the partition member which surrounds the front part of 25 the drying chamber and has a decided curvature as shown in Fig. 2, whereby the air carrying the lint from the drying chamber is deflected onto the lower face of the screen member to which the lint will adhere because of the moisture carried by the same. 30 The screen member 10 which is hinged at 13 to angle iron 37, consists of a mesh 38 provided with reinforcing U shaped strips 41 and also wiper felts 39 secured in any suitable manner to the strips 41. The felt strip at the bottom is also secured to the angle bar as shown in Fig. 6. These 35 felt strips keep the lint out of the main part of the machine casing. Strips 35 extend across the mesh as a bearing surface for rollers 14.

The other part of the delinting device as shown in Fig. 5 is termed a lint conveyor which consists of four blades 35^a arranged 40 at 90° upon shaft 34. These blades may be of any suitable rigid material and are provided at their edges with wiping strips 36^a and are also arranged in overlapping relation about the axis 34 as shown at 45 2 in Fig. 5. This part of the device is so arranged that the wiper felts 36^a neatly wipe over the lower end portion of plate 8 and also over the floor of the casing. An inclined false bottom section 44 is also provided the incline of this bottom section or plate 44 being determined by the path described by the edges of the wiper felts 36^a. In this way, the deposited lint is removed from the lower portion of the 50 chamber in front of and below the lint

collector and is transferred or conveyed to the pocket formed in the front corner of the machine casing and is prevented from being spread through this part of the machine casing. The upper end of the inclined false bottom member 44 is secured to the angle iron 37 as shown in Fig. 2. 70

From the above it will be seen that the lint carried by the air from the drying chamber will be forced through the passage-way between the wall members 8 and 9 and deflected by the curved member 8 over against the screen member 10, the air being allowed to pass on through the screen. This lint carrying more or less moisture 80 which it has accumulated upon its passing through the drying chamber will accumulate upon the screen member 10 during its periods of rest. Operation of the rollers 14 will cause a rearward swinging and 85 subsequent sudden return of the screen member to its seat 12, accompanied by a decided jarring motion which will free the lint from the screen member 10 and allow it to fall upon the blades 35^a. Then, upon 90 operation of shaft 34 at intervals, the lint received upon the horizontal blades 35^a will be thrown forwardly and formed into the pile 43 in the front part of the main casing, 95 door 44 allowing removal of such lint as desired.

An air intake is indicated at 45 and the drive shaft for the fan at 46.

What I claim is:

1. In a drying machine, the combination 100 of an air chamber, a heating chamber, a drying chamber, means for causing flow of air through said several chambers, a rockably mounted perforate lint collecting member arranged at an angle to the path of air after its passage through the drying chamber, and means for rocking said lint collecting member to remove the lint therefrom.

2. In a drying machine, the combination 105 of an air chamber, a heating chamber, a drying chamber, said chambers being enclosed by the machine casing, a door in said casing, means for causing flow of air through said several chambers, a rockably mounted perforate lint collecting member 110 arranged at an angle to the path of the air after its passage through the drying chamber, and means for rocking said lint collecting member to remove the lint therefrom, 115 said rocking means being controlled by the operation of said door.

3. In a drying machine, the combination 120 of an air chamber, a heating chamber, a drying chamber, means for causing flow of air through said several chambers, a perforate lint collector arranged at an incline to the path of air after its passage through said drying chamber, and means for jarring 125 said collector to remove the lint therefrom.

4. In a drying machine, the combination 130

- of a screen and fan chamber, a heating chamber, a drying chamber, means for forcing air through said several chambers, a rockably mounted lint collector arranged at an incline so as to intercept the lint laden air after its passage through said drying chamber, means supporting said collector in normal rest position, and means for momentarily rocking said collector 5 away from said supporting means, said collector being adapted to return and normally rest upon said supporting means.
5. In a drying machine, the combination of an air chamber, a heating chamber, a 10 drying chamber, means for causing flow of air through said several chambers, a perforate lint collector arranged at an incline to the path of air after its passage through said drying chamber, means for jarring said 15 collector to remove the lint therefrom, and a lint conveyor located in the path of the lint upon its removal from said collecting member.
6. In a drying machine, the combination 20 of an air chamber, a heating chamber, a drying chamber, means for causing flow of air through said several chambers, a perforate lint collector arranged at an incline to the path of air after its passage through 25 said drying chamber, means for jarring said collector to remove the lint therefrom, a lint conveyor located in the path of the lint upon its removal from said collecting member, and means for intermittently operating said 30 lint conveyor.
7. In a drying machine, the combination 35 of an air chamber, a heating chamber, a drying chamber, a rotary container in said drying chamber, means for rotating said container, means for causing flow of air 40 through said several chambers, a perforate lint collector arranged at an incline to the path of air after its passage through said drying chamber, means for jarring said 45 collector to remove the lint therefrom, a lint conveyor located in the path of the lint after 50 its removal from said collecting member, and means for automatically operating said 55 lint conveyor from said container.
8. In a drying machine, the combination 60 of an air chamber, a heating chamber, a drying chamber, means for causing flow of air through said several chambers, a perforate lint collector arranged at an incline to the path of air after its passage through 65 said drying chamber, means for jarring said collector to remove the lint therefrom, and a rotatable lint conveyor located in the path of the lint upon its removal from said collecting member.
9. In a drying machine, the combination 70 of an air chamber, a heating chamber, a drying chamber, means for causing flow of air through said several chambers, and a 75 perforate lint collecting member arranged to receive the air after its passage through said drying chamber, means for operating said lint collecting member to remove the lint therefrom, a lint conveyor located in the path of the lint after its removal from said collecting member, means for intermittently operating said conveyor, said last named means being operated by the said means for rotating the said drying 80 cylinder.
10. In a drying machine, the combination 85 of an air chamber, a heating chamber, a drying chamber, a drying cylinder located in said drying chamber, means for rotating said cylinder back and forth, means for causing flow of air through said several chambers, a perforate lint collecting member arranged to receive the air after its passage through said drying chamber, means for operating said lint collecting member to remove the lint therefrom, a lint conveyor located in the path of the lint after its removal from said collecting member, means for intermittently operating said conveyor, said last named means being operated by the said means for rotating the said drying 90 cylinder.
11. In a drying machine, the combination 95 of an air chamber, a heating chamber, a drying chamber, a drying cylinder located in said drying chamber, means for rotating said cylinder back and forth, means for causing flow of air through said several chambers, a perforate lint collecting member arranged to receive the air after its passage through said drying chamber, means for operating said lint collecting member to remove the lint therefrom, a rotatably mounted lint conveyor located in the path of the lint after its removal from said collecting member, means for intermittently operating said conveyor, said last named means having a drive connection with the shaft of said drying cylinder, said drive connection comprising gears upon the shafts of said drying cylinder and said conveyor, a belt connection between said gears and a 100 pawl and ratchet mechanism between the shaft of said drying cylinder and the said gear upon said last named shaft whereby said conveyor will receive intermittent operation from said drying cylinder operating 105 mechanism.
12. In a drying machine, the combination 110 of an air chamber, a heating chamber, a drying chamber, means for causing flow of air through said several chambers, an inclined perforate lint collecting member, a curved plate member having its concave face toward said lint collecting member and arranged to deflect the air after its passage through said drying chamber to said lint 115 collecting member.
13. In a drying chamber, the combination 120 of an air chamber, a heating chamber, a drying chamber, means for causing flow of air through said several chambers, a lint collecting member, a curved plate member having its concave face toward said lint collecting member, and arranged to deflect the air to said lint collecting member after its passage through the said drying chamber.

ber, means for operating said collecting member to discharge the lint therefrom, a lint conveyor arranged to receive the lint upon its discharge from said collecting member, and means for operating said lint conveyor.

14. In a drying machine, the combination of an air chamber, a heating chamber, a drying chamber, means for causing flow of air through said several chambers, an inclined perforate lint collecting member, a curved plate member having its concave face toward said lint collecting member, and arranged to deflect the air after its passage through said drying member to said lint collecting member, a lint conveyor located in the path of the lint after its removal from said collector, and having wiping engagement with the said deflector plate, and means for intermittently operating said conveyor.

15. In a drying machine, a casing enclosing an air chamber, a heating chamber, a drying chamber, means for causing flow of air through the said several chambers, a lint collector, a curved plate having its concave face toward said lint collector and arranged to deflect the air to said collector after its passage through said drying chamber, means for operating said lint collector to discharge lint therefrom, a conveyor located below the main part of said collector, the bottom portion of said casing forming a pocket to receive the lint from said conveyor and extending upwardly from a point substantially below the axis of said conveyor toward said collector, said conveyor being so arranged as to make wiping contact with the lower edge portion of said deflector and said inclined floor whereby the lint will be effectively stored in said pocket.

16. In a drying machine, the combination of an air chamber, a heating chamber, a drying chamber, said chambers being enclosed by the machine casing, a door in said casing, means for causing flow of air through said several chambers, a rockably mounted perforate lint collecting member arranged at an angle to the path of air after its passage through the drying chamber, and means for rocking said lint collecting member to remove the lint therefrom, said means comprising a lever arm mounted in operative relation to said collecting member, and having on its one end a roller for bearing engagement against said collector, a spring controlled mechanism connected to said lever arm, and means upon said door for actuating engagement with said spring controlled mechanism against the tension of said spring whereby opening or closing of said door will operate said collector.

17. In a drying machine, the combination of an air chamber, a heating chamber, a drying chamber, said chambers being en-

closed by the machine casing, a door in said casing, means for causing flow of air through said several chambers, a rockably mounted perforate lint collecting member arranged at an angle to the path of air after its passage through the drying chamber, and means for rocking said lint collecting member to remove the lint therefrom, said means comprising a lever mounted in front of said collector and having on one end thereof a roller adapted to contact with said collector, a spring controlled rod having its one end connected to the other end of said lever, a roller carried by the other end of said rod, and means carried by said casing door for momentary engagement with said roller upon operation of said door for operating said rod and lever mechanism against the tension of said spring thereby effecting operation of said collector.

18. In a drying machine, the combination of an air and blower chamber, a heating chamber, a drying chamber, means for causing flow of air through said several chambers, a curved deflector plate extending from said drying chamber and adapted to deflect the air from said drying chamber, a lint collector arranged to receive the air upon deflection from said plate, stop means to determine the extreme positions of said collector, said collector, in its normal position being adapted to rest at an incline upon said stop means, and means for moving said collector away from its normal position and then releasing the same whereby said collector will return by gravity against said rest stop with a jarring action and thereby discharge the lint therefrom.

19. In a drying machine, the combination of an air and blower chamber, a heating chamber, a drying chamber, means for causing flow of air through said several chambers, a curved deflector plate extending from said drying chamber and adapted to deflect the air from said drying chamber, a second curved plate extending from said drying chamber and forming with said deflector plate a chute for the air from the drying chamber to said deflector plate, a lint collector arranged to receive the air upon deflection from said deflector plate, stop means upon said second plate to determine the extreme positions of said collector, said collector being adapted in its normal position to rest at an incline upon said stop means, and means for moving said collector away from its normal position whereby said collector may return by gravity against said rest stop with a jarring action, and thereby discharge the lint therefrom.

20. In a delinting device for drying machine, a lint collector comprising a perforate sheet member having its edges reinforced, wiper felts secured along the reinforced edge portions, a supporting member

- for said perforate member, hinge connection between said perforate member and said support and bearing strips extending across the face of said perforate member between 5 said reinforced means for co-action with operating members.
21. In a delinting device for drying machines, a lint conveyor comprising a shaft member, a plurality of plates mounted at 10 an angle to each other upon said shaft, each of said plates extending about said axis and overlapping an adjacent plate member, and wiper felts secured along the edges of said plate members.
22. In a drying machine, a casing enclosing an air chamber, a heating chamber, a drying chamber, means for causing flow of air through said several chambers, a lint conveyor, a curved plate having its concave 15 face toward said lint collector and arranged to deflect the air to said collector after its passage through said drying chamber, means for operating said lint collector to discharge the lint therefrom, a conveyor located below the 20 main part of said collector, said casing being formed to provide a pocket to receive the lint from said conveyor, one wall of said pocket being inclined and having wiping engagement with said conveyor during its 25 operation, said conveyor making wiping contact also with said deflector plate whereby the lint will be effectively stored in said pocket, and means for allowing removal of the lint from said pocket.
23. In a drying machine, the combination of an air chamber, a heating chamber, a drying chamber, said chambers being enclosed by the machine casing, a door in 30 said casing, means for causing flow of air through the said several chambers, a lint collector arranged to receive the air after its passage through the drying chamber, means for discharging lint from said collector, said means being controlled by the 35 opening of said door.
24. In a drying machine, the combination of an air chamber, a heating chamber, a drying chamber, said chambers being enclosed by the machine casing, a door in said casing, means for causing flow of air through the 40
- said several chambers, a lint collector arranged to receive the air after its passage through the drying chamber, means for discharging lint from said collector, said means being controlled by the closing of said door. 45
25. In a drying machine, the combination of an air chamber, a heating chamber, a drying chamber, said chambers being enclosed by the machine casing, a door in said casing, means for causing flow of air through the 50 said several chambers, a lint collector arranged to receive the air after its passage through the drying chamber, means for discharging lint from said collector, said means being controlled by the opening and closing 55 of said door.
26. A drying machine, comprising a casing provided with a drying chamber, a rotatable work container therein, a lint collecting device, and a lint removing device operated by said container. 60
27. A drying machine, comprising a casing provided with a drying chamber, a work container therein rotatable alternately in opposite directions, a lint collecting device, 65 and a rotatable lint removing device actuated by said container and rotatable in one direction only.
28. A drying machine, comprising a casing provided with a drying chamber, means for producing the flow of air therethrough, and a lint collecting device located in the current of air after it passes out from the drying chamber to collect lint therefrom, said device being so arranged as to collect 70 the lint on a lower exposed surface from which it may fall by gravity.
29. A drying machine, comprising a casing provided with a drying chamber, means for producing the flow of air therethrough, a lint collecting device located in the current of air after it passes out from the drying chamber to collect lint therefrom, said device being so arranged as to collect the lint 75 on a lower exposed surface from which it may fall by gravity, and means for jarring said device to facilitate removal of lint therefrom. 80
- In testimony whereof I affix my signature.
CHARLES E. WAREAM. 85
